US0D1081104S

(12) United States Design Patent (10) Patent No.: US D1,081,104 S
(45) Date of Patent:  Jul. 1, 2025

(54) SOCK

(71) Applicant: Bauerfeind AG, Zeulenroda-Triebes (DE)

(72) Inventor: Mathias Durisch, Zeulenroda-Triebes (DE)

() Term: 15 Years

(21) Appl. No.: 35/518,671

(22) Filed: Sep. 26, 2023

(80) Hague Agreement Data

Int. Filing Date: Sep. 26, 2023

Int. Reg. No.: DM/232069

Int. Reg. Date: Sep. 26, 2023

Int. Reg. Pub. Date: Oct. 13, 2023

(30) Foreign Application Priority Data

Mar. 29, 2023 (EM) 015016235-0001

(51) LOC (15) Cl. 02-04

(52) U.S. Cl.

USPC D2/994
